IGNITING DEVICE FOR SMUDGE POTS

Sydney R. Crockett, Freeport, N. Y., assignor to
Cyril Charles Crockett, Glendale, Calif.

Application February 20, 1947, Serial No. 729,784

9 Claims. (Cl. 67—3)

1

The object of this invention is to provide an automatic igniting device for smudge pots of the type disclosed in my pending application Serial Number 719,097, filed December 28, 1946. My invention is based upon the fact that certain chemicals such as chromic anhydride, iodine crystals and potassium nitrate, when mixed into a compound in the proper proportions will ignite and produce a flame when contacted by isopropyl alcohol in the presence of oxygen or when exposed to the air.

My invention utilizes this fact for the purpose of providing a device whereby the usual oil soaked wick in a smudge pot may be ignited to produce a smudge pot for raising the temperature in order to save citrus and other fruit crops which otherwise may freeze and be destroyed.

The present invention is embodied in a device in which isopropyl alcohol is contained in an expansion chamber under pressure higher than atmospheric pressure. The alcohol is forced into the chamber at about fifteen pounds pressure above atmospheric pressure. The chamber is connected by tubing with a chemical cartridge containing a compound of the above mentioned chemicals. The flow of isopropyl alcohol to the cartridge is controlled by a normally closed valve which is automatically opened when a selected critical temperature is reached, the device of course being exposed to such temperature. When the valve is opened the isopropyl alcohol is forced out of the expansion chamber and flows to the cartridge and the latter is ignited. The present invention distinguishes over the application referred to by the feature that in this embodiment only one expansion element is employed as against two expansion elements disclosed in the said application.

The several novel features of this invention will be more fully understood from the following specification read in connection with the accompanying drawing in which

Fig. 1 is a vertical sectional view of the device with the valve in normal closed position, certain parts being broken away.

Fig. 2 is a top view of Figure 1.

Fig. 3 is a view partly in section and partly broken away showing the valve mechanism open.

Fig. 4 illustrates an ignited cartridge in a smudge pot.

The device comprises three main parts: the alcohol expansion unit 1, the valve unit 2 and the cartridge unit 3. Isopropyl alcohol as at 4 is contained within an expansion chamber 5 which has a consistent expansion and contraction characteristic. The wall of the chamber is very thin

and is therefore shown by a single line, not sectioned. The chamber is closed at the top by a cover 6 having a key 7. The cover is rotatably seated in a top disk 8 which is secured by bolts or rods 9 to a tubular valve casing 10.

The alcohol 4 is forced into the chamber 5 under a pressure of about fifteen pounds above atmospheric pressure in order to eliminate extreme barometric reactions and also in order to 10 make the chamber completely non-compressible. The chamber is constructed so as to have its major movements of expansion and contraction in one direction (up and down in the drawing) and the transverse movements due to expansion 15 and contraction are negligible.

The valve casing is closed at the bottom by a cap 11 which is secured by a set screw 12 or other means. The top disk 8, the rods 9 and the valve casing form a support for the entire apparatus 20 and encloses the operating parts as shown.

The chamber 5 carries at the bottom a nipple 14 to which there is attached a capillary tube 15 of special neoprene rubber or like material which has the property of assuming its natural formation after having been compressed therefrom. The tube 15 is the medium through which the isopropyl alcohol from the chamber 5 flows to the cartridge 3 and is operated as a valve by being compressed and released between its ends. The chamber communicates with the nipple 14 and 30 the tube 15 as indicated at 16.

The tube 15 is operated as a valve by means of a pair of springs 18, 18, which are carried by the nipple 14 and extend downward on opposite sides of tube 15. The springs have valve closing 35 fingers 19 and bent end portions 20 which engage the inner wall of a valve sleeve 24. The latter serve to compress the valve springs to close the tube. The sleeve has opposed slots 25 which serve to release the springs to open the tube as 40 shown in Figure 3. Thus the tube 15, springs 18 and sleeve 24 constitute the valve means for controlling the flow of alcohol through the tube.

The bottom cap 11 supports a flexible tubing 28 attached to the lower end of the valve tube 15. 45 The outer end of the tubing 28 is connected to the cartridge 3. The latter comprises a wax impregnated container 32 which has an inner bottom 33 of thin rubber or the like so as to be extremely flexible. The inner bottom has an opening at 34 at the side of the cartridge opposite the point of delivery of the alcohol into the container 32 from the tube 15. The opening 34 is shown much enlarged for the purpose of identification. The chemical compound 36 is placed on top of 50 the flexible bottom 33 and consists, for example,

of a mixture of 55 parts chromic anhydride, 20 parts iodine crystals and 5 parts potassium nitrate. The compound is sealed against the outside elements by a coating 40 of lacquer or the like.

Figure 1 shows the device ready for use with the tube 15 closed. The key 7 is in the "on" position, see Figure 2, to indicate that the valve springs 18 are in alignment with the release slots 25 in the sleeve 24 so that when the springs have been moved upward a sufficient distance to snap into said slots, the tube will be open. The "off" position of the key 7 is used for storage and transport of the device.

It should be noted that upon turning the key 7 fixed to the cover 6, which latter is fixed to the chamber or shell 5, the chamber and the springs 18 carried thereby are turned correspondingly. This makes it possible to dispose the ends 20 of the springs 18 in alignment with the slots 25 to set the device for operation, or out of alignment with these slots for rendering the device inoperative. Thus, with reference to Figs. 1 and 2, it will be apparent that the fingers 19 of the springs 18 will remain in position to close the tube 15 until the ends 20 move outwardly into the slots 25 and that this outward movement cannot take place when the fingers are out of alignment with the slots.

In use the igniter is carried to the field and attached to the smudge pot 50, Figure 4. Preferably the cartridge will be placed in good contact with or upon the wick in the pot. The igniter may be attached by any suitable means, such as a clip or the like, not shown, but disclosed in my aforesaid application. In the ready position the valve springs 18 are compressed to close the valve tube 15 as shown. In this position the springs are held by the sleeve 24 the inner wall of which is engaged by the end portions 20 of the springs. As the chamber 5 expands and contracts in response to temperature changes above a critical point, the springs will move axially within the sleeve 24 and the valve will remain closed.

When a critical low temperature has been reached, the chamber 5 will contract to such an extent that the ends 20 of the springs will become aligned with the release slots 25 in the sleeve 24. The springs will therefore be released from the sleeve and snap outward into the slots and the valve will automatically open. Then the isopropyl alcohol will be forced out of the chamber 5 and flow to the cartridge via the tube 15 and the tubing 28. In the cartridge the alcohol will be forced in under the flexible bottom 33 and raise the same and thereby break open the compound and rupture the coating 40 so as to expose the chemicals to the air. The alcohol will also be forced into direct contact with the chemicals through the opening 34. The result of the contact between the isopropyl alcohol and the chemicals is that instant ignition of the chemicals occur and a flame is produced. In practise it will appear as if instant combustion takes place and the cartridge becomes a flaming unit which in turn ignites the oil wick in the smudge pot to produce a smudge fire.

In preparing the device for use, the sleeve 24 will be pushed into the valve casing a distance depending upon the temperature range in which the device is to operate so that the springs will be confined and maintain the tube closed until the selected critical low temperature is reached and the springs are to be released and the tube opened. It is a feature of the present embodiment

of the invention that the major movement of expansion and contraction of the chamber 5 is in the direction toward the valve means to cause the operation thereof.

5 1 claim:

1. An igniting device for smudge pots comprising in combination a container capable of expansion and contraction at predetermined non-critical temperatures and filled with isopropyl alcohol 10 under pressure greater than atmospheric pressure, a tubular connection leading from said container, a valve mechanism in said tubular connection for controlling the passage of alcohol from the container through the connection, and 15 comprising valve springs connected to the container for closing the valve, a valve sleeve for maintaining said valve springs in valve closing position while said container expands and contracts at said predetermined non-critical temperatures, said valve sleeve having spring releasing means for releasing said springs from valve closing position at a predetermined low critical temperature, means for securing said valve sleeve stationary with relation to the container and 20 valve springs, and a chemical cartridge connected to the free end of the said tubular connection and containing a compound capable of being ignited by isopropyl alcohol from the container when the valve is open.

30 2. In an igniting device, a resilient expandable shell, rigid means secured to and preventing one end of the shell from moving responsive to expansion and contraction of the shell, a body of fluid substantially filling and tensioning the shell, 35 said fluid reducing in volume responsive to reduction of ambient temperature, a substance capable of producing a flame when combined with said fluid, means maintaining said substance in a position to be combined with fluid released from said shell; and means releasing said fluid from said shell into the presence of said substance responsive to a predetermined contraction movement of the other end of said shell.

3. In an igniting device, a resilient expandable 45 shell, rigid means secured to and preventing one end of said shell from moving responsive to contraction and expansion of the shell, a body of inflammable liquid substantially filling and tensioning said shell and which contracts responsive to reduction of ambient temperature, said shell contracting responsive to a contraction of said liquid, a substance capable of producing a flame when said liquid is combined therewith, means maintaining said substance in position to be combined with liquid released from said shell, and 55 means for releasing the liquid from said shell for contact with said substance responsive to a predetermined contracting movement of said shell.

4. In an igniting device, a resilient expandable 60 shell, rigid means secured to and preventing a portion of said shell from moving responsive to expansion and contraction of the shell and permitting expansion and contraction movement of the remainder of said shell, a body of liquid substantially filling and tensioning said shell and which reduces in volume responsive to a reduction of ambient temperature, said shell contracting responsive to the reduction in volume of said liquid, a substance which when combined with the liquid released from said shell will produce a flame, means for maintaining said substance in position to combine with the liquid released from said shell, and means for releasing the liquid from said shell responsive to a predetermined movement of said shell.

5. In an igniting device, a resilient expandible shell adapted to be substantially filled with a liquid which will change in volume responsive to changes in ambient temperature, a rigid means secured to and preventing a portion of said shell from moving responsive to expansion and contraction of the shell, means for maintaining a substance which will produce a flame when in contact with liquid released from said shell, in a position to contact liquid released from the shell, and means for releasing liquid from the shell into contact with said substance responsive to a predetermined movement of the shell.

6. A device comprising, a resilient shell adapted to be substantially filled with a liquid which will change in volume responsive to changes in ambient temperature, rigid means secured to and preventing a portion of said shell from moving responsive to expansion and contraction of the shell, and means connected with said shell for releasing liquid from the shell responsive to a predetermined movement of the shell according to the change in volume of said liquid.

7. A device comprising a resilient shell, rigid means secured to and preventing one end of said shell from moving responsive to expansion and contraction of the shell, a body of liquid substantially filling and tensioning said shell and which contracts responsive to reduction of the temperature to which the shell and liquid are subjected, the other end of the shell moving toward said one end responsive to reduction of the volume of said liquid, and means connected with said shell for releasing the liquid from the shell responsive to a predetermined movement of said other end of said shell toward said one end.

8. In an igniting device, a single resilient expandible shell, a rigid means secured to one end of said shell, a body of liquid substantially filling

said shell and contracting responsive to reduction in ambient temperature, said single shell and said body of liquid constituting the sole means for moving said shell, said shell contracting solely in response to a temperature-effected contraction of said body of liquid, a substance which in combination with the liquid released from the shell will produce a flame, means maintaining said substance in position to be combined with liquid released from said shell, and means connected with the shell and responding to contraction of the shell for releasing the liquid into contact with said substance.

9. A device comprising, a resilient shell adapted to be substantially filled with a liquid which will change in volume responsive to changes in ambient temperature, rigid means secured to and preventing a portion of said shell from moving responsive to expansion and contraction of the shell, means connected with said shell for releasing liquid from the shell responsive to a predetermined movement of the shell, according to the change in volume of said liquid, means on said rigid means for rotating said shell, and means responsive to rotation of said shell for rendering said releasing means inoperative.
